F. C. BILLINGS.
MUSIC ROLL FOR PLAYER PIANOS.
APPLICATION FILED MAR. 30, 1917.

Patented Aug. 27, 1918.

* There are two classes of Time, Duple and Triple. In Duple time, the number of beats to the measure is divisible by 2; in Triple time by 3.

MUSIC-ROLL FOR PLAYER-PIANOS

1,277,180.

Specification of Letters Patent. Patented Aug. 27, 1918.

Application filed March 30, 1917. Serial No. 158,514.

To all whom it may concern:

Be it known that I, FREDERICK C. BILLINGS, a citizen of the United States, residing at the city of Milwaukee, county of Milwaukee, and State of Wisconsin, have invented new and useful Improvements in Music-Rolls for Player-Pianos, of which the following is a specification.

My invention relates to improvements in player piano music rolls. The object of my invention is to provide means whereby such music rolls may be employed to facilitate teaching music, the exercise, or set of exercises, being printed upon the roll in a position for exposure to view, preparatory to the passage of the perforate portion of the sheet over the tracker bar, and fragments of the exercise, representative of the individual perforations of the series, being also displayed over the tracker bar simultaneously, or substantially simultaneously, with the sounding of the notes by the mechanical operation of the player piano.

I thus propose to enable the pupil to manually play the exercise, and subsequently have the exercise repeated mechanically, the pupil reading the notes during both operations, *i. e.*, while manually playing the exercise and while the same is being mechanically played.

The drawing illustrates a fragment of a music roll, embodying my invention, said fragment including a printed exercise adapted to be read and manually played by the pupil, and also including the initial portion of the same exercise as represented by perforations and printed fragments of the same in lineal series upon the strip of paper composing the roll. My improved music strip includes a set of instructions printed upon a portion A of the strip adjacent to the connecting tab B', whereby the strip may be secured to the receiving roll of a piano player. The instruction section A of the strip is followed by a section B containing the printed music scale and staff, as in all ordinary instruction books, this constituting the first section, or element, of the exercise and being followed successively by additional sections C, D and E.

Section B, in the exercise illustrated, comprises the scale printed in full notes, as an ascending scale. Section C illustrates the descending scale, similarly printed. Sec-

tion D includes both the ascending and descending scale, printed in half notes, and section E includes the same, printed in quarter notes.

These several sections A, B, C, D and E are so arranged upon the strip that they may be successively exposed upon or in the vicinity of the tracker bar, the strip being advanced mechanically by the player piano, and its motion arrested by operation of the controlling lever, with which such pianos are provided. Player pianos are also provided with reverse levers, whereby the strip may be retracted at pleasure, and by thus advancing and retracting the strip to suit the requirements of the pupil various sections of the exercise may be successively played manually without confusion. The section to be played is invariably presented in a predetermined relation to the tracker bar.

The section F of the strip is perforated, in the ordinary manner, to control the action of the player piano in mechanically reproducing the exercise printed to sections A to E inclusive, whereby the strip may be continuously advanced after the pupil has inspected or played the practice sections A to E inclusive, and the exercise mechanically repeated. But, in order to enable the pupil to associate each sound, thus mechanically produced, with the printed portion of the exercise which it represents, I print a fragment of a musical scale in a position laterally offset from each perforation, and in an imperforated border portion, this fragment of the scale containing a printed note, or set of notes, associated with the adjacent perforations, or set of perforations, in such a manner that the pupil will be enabled to read the music simultaneously with the sound of the exposed printed notes by the player piano. In this manner the pupil readily learns to associate the printed notes with the sounds which those notes represent. The staff lines in each fragment extend horizontally, *i. e.*, transversely of the strip, as indicated at f, f' in the drawing. The staff and the printed notes thereon are therefore displayed in the same manner as any ordinary printed song book or music sheet, with the exception that the staff is subdivided into fragments, and the fragments arranged in a lineal series, whereby

the notes upon each fragment may be associated with the perforations which produce such notes.

From the foregoing description it will be apparent that a pupil using my improved music roll may not only practice his exercise manually in the ordinary manner, but may at any time, by advancing the strip, cause any portion of the exercise to be played mechanically, and he may simultaneously inspect the portion of the exercise which is being played, and associate the printed characters with the sounds which they represent, after which the strip may be retracted and the exercise repeated manually.

I attach great importance to the fact that my invention provides for the manual performance of the exercise independently of the mechanical reproduction thereof, and also provides means whereby the pupil may not only listen to the mechanical reproduction of the exercise, and simultaneously read the same and associate the printed characters with the sounds mechanically produced, but the pupil may also accompany the instrument by manually fingering the keys simultaneously with their mechanical operation. The pupil will soon learn to slightly anticipate the depression of each key, the mechanical depression of the keys correcting any errors which he may make. In this manner the pupil learns to read the music very quickly, and the staff lines being printed horizontally with the notes thereon in conventional form, it is obvious that any pupil who has learned to read music by using my improved roll may subsequently learn it with equal facility from a book or music sheet, all the conventional signs and symbols being similarly displayed, and the music being read from left to right on the music roll in the same manner as upon a printed page or sheet.

The only difference between reading the exercise from the music roll and the act of reading it from a printed sheet or page of ordinary music, is that I preferably read the lines from the bottom to the top successively, instead of commencing at the top and reading to the bottom. This is done merely in order that while reading the music the same

may be advanced over the tracker bar in the direction of the perforated portion of the sheet.

I claim:—

1. A music instruction roll for player pianos, comprising a strip having an imperforate portion, a printed musical exercise upon said portion subdivided into transversely extending sections adapted for successive exposure upon the tracker bar of a player piano, the said strip having a series of perforations in another portion of the roll adapted to cause the mechanical reproduction of the same exercise by a player piano when used in connection therewith, whereby a student may have the exercise mechanically played in alternation with efforts to read the music as printed upon the imperforate portion of the roll and to play the same manually upon the instrument with which the roll is used.

2. A music instruction roll for player pianos, comprising a strip having an imperforate portion, a printed exercise upon said portion subdivided into transversely extending sections adapted for successive exposure upon the tracker bar without exposing perforations thereon, said strip being provided with a perforate portion adapted to mechanically reproduce the same exercise when used in connection with a player piano, said perforate portion having an imperforate border portion provided with printed fragments displaying portions of the exercise and arranged in lineal series, each such printed fragment being laterally offset from perforations productive of the sounds represented by the notes on the printed fragment, whereby a student may alternately play the exercise upon the piano while the imperforate portion is being passed over the tracker bar, and then read the same exercise on the imperforate border portion while the sounds are being mechanically reproduced as the perforate portion traverses the tracker bar.

In testimony whereof I affix my signature in the presence of two witnesses.

FREDERICK C. BILLINGS.
